Des. 232,196
Patented July 23, 1974

232,196

PAINT ROLLER

John F. Mason, Phoenix, Ariz. (Building 450-B,
Mickley Run Apts., Whitehall, Pa. 18052)

Filed Nov. 15, 1972, Ser. No. 306,534

Term of patent 14 years

Int. Cl. D8—05

U.S. Cl. D64—18

FIG. 1.

FIG. 2.

FIG. 3.

FIG. 4.

FIG. 5.

FIG. 1 is a front perspective view of the paint roller showing my new design;

FIG. 2 is a reduced front elevational view thereof;

FIG. 3 is a side elevational view thereof;

FIG. 4 is a rear elevational view thereof; and

FIG. 5 is a bottom plan view thereof.

I claim:

The ornamental design for a paint roller, as shown.
